Application July 20, 1939, Serial No. 86,104

Term of patent 3½ years

To all whom it may concern:

Be it known that I, Ora Jurs, a citizen of the United States, residing at Chicago, in the county of Cook and State of Illinois, have invented a new, original, and ornamental Design for a Display Sign or Similar article, of which the following is a specification, reference being had to the accompanying drawing, forming part thereof.

Figure 1 is a front perspective view of a display sign or similar article embodying my new design.

Figure 2 is a side elevational view thereof.

I claim:

The ornamental design for a display sign or similar article, substantially as shown.

ORA JURS.
